A. J. WORKS, OF FAIR HAVEN, CONNECTICUT.

Letters Patent No. 61,131, dated January 8, 1867.

IMPROVED MODE OF BURNING HYDRO-CARBON LIQUIDS AS FUEL.

The Schedule referred to in these Letters Patent and making part of the same.

TO ALL WHOM IT MAY CONCERN:

Be it known that I, A. J. WORKS, of Fair Haven, in the county of New Haven, and State of Connecticut, have invented a new and useful improvement in using Hydro-Carbon Liquids and Hydrogen Gas as Fuel; and I do hereby declare that the following is a full, clear, and exact description thereof, which will enable others skilled in the art to make and use the same, reference being had to the accompanying drawing, forming part of this specification, in which drawing—

Figure 1 represents a transverse vertical section of an apparatus used in carrying out this invention.

Figure 2 is a horizontal section of the same.

This invention relates to the use of petroleum, or other hydro-carbon liquids, or the vapors thereof, or the constituent gases thereof, which are burned in open troughs or receivers surrounded by air-channels, in connection with jets of decomposed steam or hydrogen gas thrown upon the liquid or into the flames thereof, in such a manner that a perfect combustion of the hydro-carbon liquid is effected, and an intense heat is produced. The decomposition of the steam is effected in a chamber which is filled with charcoal or coke, and which is situated above the receivers in such a manner that it serves as a shield to protect the exposed parts of the boiler, still, or other thing under which the apparatus or burner is used, and to compress the flames of the hydro-carbon liquids, and prevent the escape of unconsumed carbon, and that it is heated by the action of said flames, and thereby the decomposition of the steam is facilitated. The decomposed steam issues from the decomposer through a series of jets, and is discharged in volumes of flame, or as decomposed steam, intensely heated, on the surface of the hydro-carbon liquid in the lower receiver, so that the vaporization of said liquid is greatly facilitated, and the flame or gases issuing from the openings in the decomposer are intimately mixed with the vapors and gases arising from the receivers, and thereby the use of heavy oils, such as crude petroleum, for fuel, is rendered highly practicable and economical.

The letter A represents or designates a receiver, which, by preference, is made annular and oblong, as shown in fig. 2 of the drawing, but which may be made in any other suitable form or shape. In the interior of this receiver is situated a secondary receiver, B, which is supported by the standards a, or any other suitable means, and into this interior receiver I introduce petroleum, or other hydro-carbon liquid, through a pipe, b, which connects with the oil reservoir C. As the secondary receiver B fills with oil, said oil overflows into the main receiver A, the bottom of which is covered with pumice stone, or other refractory and absorbent material, whereby the liquid is spread over a large evaporating surface, and its vaporization is materially facilitated. The receiver A is supported by beams, D, and it is surrounded by a jacket, E, leaving a central air-channel, e, in the interior, and an annular air-channel, d, round said trough, so that a full supply of atmospheric air is admitted to support the combustion of the gases emanating from the troughs A B, and from the decomposer F. This decomposer is supported by a pipe, e, which rises up through the central air-channel e, and it extends down within the jacket E, as shown in fig. 1 of the drawing. If desired, the decomposer may be further supported by bolts tapped into and resting on the cross-bars. On the top edge of said jacket, and properly supported, rests a head, G, whereby the burning vapors and gases emanating from the receivers and from the decomposer are thrown in contact with the sides of said decomposer, so as to heat the same, or its contents, to the proper temperature to effect the decomposition of steam. Steam is admitted to said "decomposer" through a pipe, e, which connects with a steam-boiler or other suitable steam generator, H, and the top of said decomposer is made movable, so that it can be taken off for the purpose of introducing charcoal, coke, or other material by which the decomposition of the steam is produced. As the steam passes through the incandescent charcoal, coke, or other material in the decomposer, it is decomposed into hydrogen and carbonic oxide gases, and these gases issue through a series of openings near the bottom of the decomposer. In order to permit these jets of gas, or the flames thereof, to strike the surface of the oil in the main receiver A, the inner edge of said receiver is bevelled or made beveling, as clearly shown in fig. 1, and as the heated gases, &c., issuing from the decomposer, strike the surface of the overflowing oil in the receiver A, they facilitate the vaporization thereof, so that the heavier oils, such, for instance, as crude petroleum, of any degree of gravity, can be used with advantage as fuel in every kind of furnace or fire-box. The vapors or gases rising from the oil in the receivers mingle intimately with the gases, or are ignited by the flames issuing from the decomposer, and a gas compound or flame is obtained

which produces an intense heat. The decomposer being placed over the receivers A B, and being provided with gas openings, *f*, below, forms a shield which prevents the escape of unconsumed carbon, and the oil is burned with great economy. In practice my burner will be surrounded by a brick wall, so that no air is admitted to the flames except through the air-channels *c d*. This burner is applicable to refineries, steam boilers, and, in fact, for furnaces of any description whatever where an intense heat is required. It might be remarked that this process and apparatus have already been practically applied in a large number of refineries and steam boilers, and for several months past worked and used therein with very great success, economy, and satisfaction. When applied to refineries, the refuse thereof, used in the above manner, is found sufficient to work the same, and no other fuel whatever is required. In applying my invention to steam-boilers, &c., the hydro-carbon can be ignited and burned alone until steam is raised in the boiler sufficient to flow through the pipe, when it can be allowed to pass into the decomposer. But in case of marine, locomotive, or other large boilers or furnaces, it is well to use a small temporary boiler to furnish steam until the steam begins to generate in the large one, when the small one is dispensed with, and the heating proceeds in an increased ratio or degree. Waste steam or water may be used, and so the power of the engines be not interfered with.

Having thus described my invention, what I claim as new, and desire to secure by Letters Patent, is—

1. The combustion of naphtha, crude petroleum, or any other liquid hydro-carbon, on an open surface or receiver connected or surrounded with air-channels in connection with ignited hydrogen gas, the flames of both uniting while in a state of combustion, substantially as and for the purpose set forth.
2. I also claim the arrangement of a series of receivers, two or more, in combination with each other and with a suitable supply pipe, constructed and operating substantially as and for the purpose described.
3. I also claim the secondary receiver B, in combination with the main receiver A, substantially as and for the purposes described.
4. I also claim the central air-channel *c*, and annular air-channel *d*, in combination with the receiver A, constructed and operating substantially as and for the purpose described.
5. I also claim the decomposer F, provided with jet openings *f* near its bottom, in combination with the jacket E, receivers A B, and air-channels *c d*, all constructed and operating substantially as and for the purposes set forth.
6. I also claim the hood G, in combination with the jacket E, decomposer F, receivers A B, and air-channels *c d*, all constructed and operating substantially as set forth.

The above specification signed by me this 1st day of December, 1866.

A. J. WORKS.
